239,040

FISH FEEDER OR THE LIKE

Robert F. Evans, P.O. Box 62, La Mirada, Calif. 90637

Filed July 15, 1974, Ser. No. 488,723

Term of patent 14 years

Int. Cl. D30—03

U.S. Cl. D30—13

FIG. 1 is a left side elevational view of a fish feeder showing my new design;

FIG. 2 is a front elevational view;

FIG. 3 is a right side elevational view; and

FIG. 4 is a rear elevational view.

I claim:

The ornamental design for a fish feeder or the like, substantially as shown.
